COMBINED TOOTH CLEANING AND GUM MASSAGING DEVICE

Application filed July 9, 1930. Serial No. 466,833.

Our invention is a novel combined tooth cleaning and gum massaging device, and the principal object thereof is to provide a simple, efficient, and practical device which will 5 not only clean the surfaces of the teeth but will also massage the gums and clean the interdental spaces between the teeth, the device being so designed that all parts of the teeth and gums not accessible to the ordinary 10 toothbrush may be readily engaged by the device and cleaned.

It is well known that the ordinary toothbrush of the bristle type will not reach all 15 parts of the teeth particularly distal surfaces of the posterior teeth upon which food and mucin collect, nor will the ordinary toothbrush properly clean the mesio or distal surfaces of teeth forming a gap where a tooth has been extracted, the reason being 20 that the bristles merely bend across the teeth under pressure instead of following the contour of the teeth. Our novel device provides a yieldable upper body having one set of parallel wedge-shaped ribs disposed longitudinally of the handle, and another set 25 of parallel substantially semi-circular ribs with pointed ends disposed transversely of the handle and will fit into and take the shape of any interdental space or gap into 30 which the device is inserted.

We will explain our invention with reference to the accompanying drawings which illustrates several practical embodiments thereof to enable others familiar with the 35 art to adopt and use the same; and will summarize in the claims the novel and essential features of construction for which protection is desired.

In said drawings:

40 Fig. 1 is a perspective view of our preferred form of device.

Fig. 2 is a longitudinal section therethrough.

45 Fig. 3 is a side elevation of a set of upper teeth and adjacent portions of the gum showing our novel device in various positions with respect thereto.

50 Fig. 4 is a plan view of a set of lower teeth showing our novel device in various positions with respect thereto.

Fig. 5 is a side elevation showing a modified form of device.

Figs. 6, 7 and 8 are views showing various uses of the device.

As shown, our preferred form of combined 55 tooth brushing and gum massaging device comprises an elastic or yielding body member having a bore 2 for a handle 3 and a series of parallel substantially semi-circularly shaped ribs 1 integral with the body and extending from one side of the body as shown in Fig. 1, the ribs 1 being disposed transversely of the bore 2. Bore 2 is adapted to receive the end of a handle 3 which is provided with a collar 3a adjacent one end, and a knob 3b 60 on the outer end adapted to yieldably engage a recess 2a in the outer end of the bore 2 whereby the body will be yieldably retained on the handle 3 between the parts 3a and 3b and may be easily removed therefrom when 65 it is desired to interchange the body. Preferably the ends of the ribs 1 are pointed as at 1a (see Figs. 1 and 3) for the purpose hereinafter set forth, and the ribs 1 (3 being shown) which extend transversely of the handle 3 are thinned at their outer edges.

Diametrically opposite the ribs 1 and formed integrally with the body is a series of longitudinally disposed ribs 4 (3 being shown) extending slightly beyond the outer 80 surfaces of the end ribs 1, the ends 4a of ribs 4 being angularly disposed with respect to the plane of the outer ribs 1 for the purpose hereinafter set forth, whereby ribs 4 are 85 formed substantially wedge-shaped with the wider portion of the ribs outermost, as indicated in Fig. 2. The ribs 4 are also thinned adjacent their outer edges as clearly indicated in the drawings.

The modification shown in Fig. 5 differs 90 from that shown in Figs. 1 and 2 with respect to the number of ribs 1 (five being shown in said modification), and also differs with respect to the shape of the ribs 4 one end of which is rounded as at 4b instead of being truly wedge shaped, and the modified form shown in Fig. 5 would necessarily be somewhat longer and larger than that shown in Fig. 1.

100 The wedge shape of ribs 4 in our device is

an important feature, for as illustrated in Fig. 3 when the device is reciprocated sideways in a gap formed by extraction of a tooth or teeth, as shown in the position A, the ribs 4 will enter the gap and as the ribs 4 are wedge-shaped the outer corners thereof will contact with the adjacent faces of the teeth at their gum lines and effectively clean all matter from the faces of the teeth as the device 10 is moved transversely of the row of teeth. At the same time the outer arcuate edges of the ribs 4 will clean the surface of the gum lying in the gap thereby cleaning both the mesio and distal surfaces of the adjacent teeth as 15 well as the gum at the point where one or more teeth have been extracted.

In the position "B" indicated in Fig. 3 the edges of the ribs 4 engage the distal surfaces of the rearmost teeth at the gum line and effectively clean all portions of such surface.

The transversely disposed disks 1 may be used, as illustrated at "C" in Fig. 3, to clean all surfaces of the gums and also the surfaces of the teeth. For cleaning the interdental 25 space at cervix of the gum line however the device may be rotated through an angle of 90° to bring the sharply pointed ends 1a of the transverse ribs 1 into position to engage or fit into such interdental spaces at the gum 30 line as shown in Figs. 6 and 8, and by reason of the sharp pointed ends the same will enter between the teeth and effectively clean the interdental spaces of teeth and cause a healthy circulation.

35 In Fig. 4 the transverse ribs 1, in position "D", are used for massaging under the tongue and the gums at the lingual surface of the teeth. In position "E" the transverse ribs 1 are shown operating upon the occlusal 40 surface of the lower molars. In Fig. 7 the longitudinal ribs 4 are shown in position for cleaning the interdental spaces at the lingual surface of the upper and lower teeth.

We have not herein attempted to illustrate 45 every position and use of our device, as it will be obvious that every portion of the gums and teeth which are not accessible with an ordinary tooth brush may be readily massaged or brushed leaving the gums and teeth 50 clean and healthy. Actual tests have been made to prove that only 3 ounce pressure can be made with the bristles in a sweeping motion. It takes 5 pound pressure in the interdental spaces and surrounding tissue to 55 bring about a healthy circulation. Heavy pressure can be used with this device which hardens the tissue and causes healthy condition of gums.

60 Also our device is much smaller than an ordinary toothbrush and can be applied to any part of the oral cavity without discomfort.

We do not limit our invention to the exact 65 forms shown in the drawing for obviously

changes may be made therein within the scope of the claims.

We claim:—

1. A device of the character specified, comprising a yielding body having a handle; a series of flexible segmental ribs on said body disposed parallel with the handle; and a second series of flexible ribs disposed transversely of said handle; the ribs in each series being substantially the same size. 75

2. A device of the character specified comprising a yielding body having a handle; a series of flexible segmental parallel ribs on said body disposed longitudinally of said handle; and a second series of flexible parallel ribs disposed transversely of said handle; said longitudinally disposed ribs being substantially wedge-shaped with their wider portions outermost. 80

3. A device of the character specified comprising a yielding body having a handle; a series of flexible parallel ribs on said body disposed longitudinally of said handle; and a second series of flexible parallel ribs disposed transversely of said handle; said transverse ribs being substantially semi-circular and having their outer ends pointed. 85

4. A device of the character specified comprising a yielding body having a handle; a series of flexible parallel ribs on said body disposed longitudinally of said handle; and a second series of flexible parallel ribs disposed transversely of said handle; said longitudinal ribs being substantially wedge-shaped with their wider portions outermost, and said transverse ribs being substantially semi-circular and having their outer ends pointed. 95

5. A device of the character specified comprising a yielding body having a bore; a handle in said bore; a series of flexible substantially wedge-shaped ribs on said body disposed parallel with said bore; and a series of flexible substantially semi-circular ribs on said body disposed transversely of said bore; the ribs in each series being substantially the same size. 105
